REACTANCE CONTROLLED GENERATOR

Howard C. Lawrence, Haddon Heights, N. J., assignor to Radio Corporation of America, a corporation of Delaware

Application June 19, 1942, Serial No. 447,696

8 Claims. (Cl. 179—171.5)

The remote control of radio receivers often necessitates control of an oscillator. When the oscillator must be controlled over a wide frequency range some form of motor driven or flexible shaft driven capacitor is usually used. When the tuning range is small, however, as is the case when adjusting a beat-frequency oscillator to obtain the desired audio frequency output or when an adjustment of the frequency of the heterodyning oscillator associated with the first detector is necessary to compensate for a frequency drift in the receiver or transmitter, simplified control systems are possible. One such system involves the use of a reactance tube connected across the oscillator tank circuit. The usual reactance tube and oscillator circuit requires the use of two tubes. Compact design such as is necessary in mobile equipment makes it desirable to use a single tube for this purpose. In this application I disclose a new and improved reactance tube and controlled oscillator including a single tube.

This oscillation generator may also be used as the generator and modulator in a wave length modulation system, in which case the variable reactance effect produced in the generator tube is controlled by signals to correspondingly control the length of the oscillations generated.

In describing my invention reference will be made to the attached drawing wherein:

Figure 1 illustrates by circuit diagram a controlled oscillation generator arranged in accordance with my invention;

Figure 2 is a vector diagram used to illustrate the operation of my controlled generator; while

Figures 3 and 4 are modifications of the arrangement of Figure 1.

The circuit shown in Figure 1 is an oscillator and reactance tube control system using a single pentode tube. The frequency range of the oscillator can be made controllable over a range of at least 2% by means of a variation in the direct current potential applied to one element of this tube. The absence of any radio frequency voltage on the controlled circuit makes it possible to use unshielded wires within a power cable for the control leads.

The cathode 4, grid 6 and screen grid 8 of tube V are connected as a conventional triode grounded-plate Hartley oscillator having a tank circuit 12. The screen is bypassed to ground for radio frequency and direct current voltage applied through resistor R2 to give the proper screen voltage. Resistor R3 in the plate circuit of V is chosen to give the maximum available

radio frequency output voltage at the plate of the tube when the frequency control R4 is set at the maximum direct current voltage position. Too large a load resistor will cause low output voltage because of the low direct current plate voltage present at the tube, while too small a resistor will cause low output voltage because of the low radio frequency impedance of the plate load. A tuned circuit or radio frequency choke may be substituted for this load although this will change the amount of frequency shift obtainable and introduce the possibility of a new mode of oscillation if the circuits are not properly adjusted.

C3 is of such a value that a maximum reactive component of the plate voltage is fed back to the resonant circuit 12. It should be made small to obtain maximum phase shift and yet large to obtain minimum attenuation. The optimum conditions are most easily obtained from the vector diagrams, Figure 2. The plate voltage is represented by the vector ER3 at zero degrees phase angle. The voltage drop, Ec, across C3, and the voltage drop EL across the resonant circuit must add up to ER3. At resonance the parallel circuit L1 C1 appears as a resistance of magnitude $Q\omega L1$ or

$$\frac{Q}{\omega C1}$$

The voltage across L1 C1 is therefore 90° out of phase with that across the feedback capacitor C3. The reactive component of Ec has as its locus a semi-circle the diameter of which is ER3.

It is evident that the maximum reactive component of voltage is obtained when $EL=Ec$ and the maximum amplitude is one-half ER3. Then:

$$\frac{1}{\omega C3} = Q\omega L1 = \frac{Q}{\omega C1}$$

or

$$C3 = \frac{C1}{Q}$$

where Q is that of the resonant circuit L1 C1. When these conditions exist, a voltage is fed back from the plate of V to the resonant circuit 45° out of phase with that normally appearing at the grid of V. The plate circuit of the tube therefore appears to the resonant circuit as a capacity. The magnitude of this capacity depends upon the radio frequency voltage available across R3. This available radio frequency voltage is controlled by the plate voltage applied to the tube by po-

tentiometer R4. The dotted lines in Figure 2 show conditions when the capacity C3 is of too small value.

An adjustment of the potential on the anode 14 of tube V1 changes the magnitude of the complex impedance (which here is capacitive in character) applied by C3 across the resonant circuit L1 C1. This variable reactance is part of the resonant circuit L1 C1 and determines in part the frequency of the generated oscillations. The change in potential on the plate 14 of the tube may correspond to automatic frequency control potentials or to signals or other control potentials applied to the leads across condenser C5 in Figure 1 marked "Control potentials" or to the transformer T1 of Figure 3. C5 is then small enough not to bypass the control or modulation potentials.

In Figure 3, as in Figure 1, L1 and C1 is the circuit resonant at the oscillator frequency. R1 supplies proper bias to the grid. Condenser C2 bypasses the resistance R1. Condenser C3 provides the proper phase shift in the generated voltage fed back to L1 C1 and the grid 6.

$$C_3 \text{ equals } \frac{C_1}{Q}$$

where Q is that of the resonant circuit L1—C1. R3 is the plate voltage supply resistance and also the radio frequency load. The transformer T1 secondary is bypassed for radio frequency by condenser C5. The potential on the screen electrode 8 is usually higher than that on the plate 14.

I have shown in Figure 4 a balanced oscillator using the principle used in Figures 1 and 3. In Figure 4 the various elements have been designated by the same numerals used in Figures 1 and 3.

L1 and C1 are of such values that they produce the desired oscillation frequency. R4, R1, C2 and C2' provide proper grid bias and radio frequency bypass action respectively. C4 and C5 are radio frequency bypasses on the direct current voltage sources. R3 and R3' are load elements at the radio frequency. They may be resistors, tuned circuits or other type components. C3 and C3' feed back radio frequency voltage developed across R3 and R3' and at the same time shift the phase of this voltage, causing the plate circuit to look like a capacity, the value of which depends on plate voltage. Frequency control is by variation of modulation of the plate voltage.

The operation thereof is in general as set forth in detail above. In Figure 4 the oscillator plate potential is never higher than the screen potential where linear control is desired. In this modification

$$C_3 = C_3' = \frac{C_1}{4Q}$$

where Q is that of the resonant circuit L1—C1.

Plate modulation or control is used with the control or modulation potential applied between lead 20 and ground. The plate potential at 20 may be modulated at an audio rate for frequency modulation or controlled by a potentiometer from a local or remote point for generator frequency control.

The oscillator shown in Figure 1 operates at 200 kc. It has a controllable frequency range of 4000 cycles when operated from a 200 volt B supply. Three different 9001 tubes checked in this circuit gave a controllable frequency range of between 4000 and 5000 cycles. It can be seen that this will vary somewhat with the Gm of the tube, since this Gm determines the radio fre-

quency voltage available at the plate. The oscillator output voltage varied between 25 and 35 volts for one particular tube as the plate voltage was varied between 0 and +200 volts. Screen current changed from 0.45 to 0.35 millampere and the plate current changed from 0 to 0.3 millampere.

Frequency stability of this oscillator is such that when the supply voltage to the complete receiver was dropped 25%, the oscillator frequency varied .005% at one extreme of the frequency control and .06% at the other extreme. It is possible to arrange the oscillator in such a way that the frequency shift is slightly negative with a change in battery voltage at one extreme of the controllable range and slightly positive at the other extreme, giving a minimum frequency change for a change in battery voltage for all settings of the frequency control. The choice of screen dropping resistor R2, grid resistor R1, grid coupling capacitor C2 and the position of the tap on oscillator coil L1, as well as the LC ratio of the resonant circuit will determine the stability of the oscillator. These values should be carefully considered to obtain best stability.

The output voltage of the oscillator may be maintained within closer limits by reducing the range over which the plate voltage of V1 may be varied. It is suggested that this range always start at 0 volts plate since this is the condition of minimum effect of battery voltage due to change in Gm of the tube upon the frequency of the oscillator. A small capacity across R3 will similarly stabilize the output voltage but at the same time will reduce the controllable frequency range.

In an oscillator arranged as in Figure 1 to generate oscillations at 200 kc. the elements shown had the following values:

40	C1	μuf	600
	C2	μuf	500
	C3	μuf	17
	C4	μf	0.004
	C5	μf	0.1
45	R1	ohms	150,000
	R2	do	33,000
	R3	do	47,000
	R4	do	100,000
50	V	Type 9001 tube	
	B+	volts	200

The output voltage is taken from L1 through either a small capacitor, tap on winding, or, as shown, by an auxiliary winding coupled to L1.

I claim:

55. 1. In means for supplying a controllable reactive effect across a resonant circuit in which alternating current flows, an electron discharge device having electrodes including a control electrode coupled with said resonant circuit and an additional electron receiving electrode coupled to the aforesaid electrodes by the electron stream of the device, a phase shifting reactance coupling said electron receiving electrode to said control electrode for feeding thereto alternating voltage 65 a component of which is displaced in phase substantially 90° with respect to the alternating voltage appearing on said control electrode due to its connection to said resonant circuit, whereby a reactive effect is added to said resonant circuit, and connections for adjusting the potential on said additional electrode to vary the voltage fed to the control electrode and thereby vary said reactive effect.

70. 2. In means for supplying a controllable reactive effect across a resonant circuit in which

alternating current flows, an electron discharge device having an anode-like electrode, a cathode and a control electrode coupled with said resonant circuit and an additional electron receiving electrode coupled to the aforesaid electrodes by the electron stream of the device, connections for applying a direct current potential to said anode-like electrode, an impedance for applying direct current potential of less value to said additional electrode, a phase shifting reactance coupling said electron receiving electrode to said control electrode for feeding thereto alternating voltage a component of which is displaced in phase substantially 90° with respect to the alternating voltage appearing on said control electrode due to its connection to said resonant circuit, whereby a reactive effect is added to said resonant circuit, and connections for varying the direct current potential applied to said additional electrode to vary the voltage fed to the control electrode and thereby vary said reactive effect.

3. In means for supplying a controllable reactive effect across a resonant circuit in which alternating current flows, a pair of electron discharge systems having electrodes including a control electrode coupled with said resonant circuit and an additional electron receiving electrode coupled to the aforesaid electrodes by the electron stream of the device, a phase shifting reactance coupling the electron receiving electrode of one of said systems to the control electrode of said one of said systems, a phase shifting reactance coupling the electron receiving electrode of the other system to the control electrode of the other system, said phase shifting reactances feeding back to said control electrodes alternating voltages displaced in phase with respect to the alternating voltages appearing on said control electrodes due to their coupling to said resonant circuit, and means for applying variable direct current potentials in phase to said electron receiving electrodes.

4. In a controllable frequency generator, an electron discharge device having oscillation generating electrodes including a control electrode in an oscillation generating circuit, and an additional electron receiving electrode coupled to the generating electrodes by the electron stream of the device, a phase shifting reactance coupling said electron receiving electrode to said generating circuit for feeding thereto a voltage of the generated frequency a component of which is displaced in phase about 90° with respect to the generated voltage, whereby a reactive effect is added to said resonant circuit and connections for applying a variable potential to said additional electrode to vary said reactive effect.

5. In a system for generating waves of controllable frequency, an electron discharge device having oscillation generation electrodes including a control grid in an oscillation generating circuit and an additional electron receiving electrode coupled to the generating electrodes by the electron stream of the device, a phase shifting reactance coupling said electron receiving electrode to said control electrode for feeding thereto a voltage of the generated frequency a component of which is displaced in phase about 90° with respect to the generated voltage on said control electrode, whereby a reactive effect is produced by said device in said generating circuit to determine in part the frequency of the oscillations generated, and means for varying the potential

on an electrode of said device to vary said reactive effect and thereby vary the frequency of the oscillations generated.

6. In a wave length modulation system, an electron discharge device having oscillation generation electrodes including a control grid in an oscillation generating circuit and an additional electron receiving electrode coupled to the generating electrodes by the electron stream of the device, a phase shifting reactance coupling said electron receiving electrode to said control electrode for feeding thereto a voltage having a component displaced about 90° in phase with respect to the generated voltage on said control electrode, whereby a reactive effect is produced in the generating circuit to control the frequency of the oscillations generated, and connections for varying the potential on said electron receiving electrode of said device in accordance with signals to vary said reactive effect and thereby vary the frequency of the oscillations generated in accordance with signals.

7. In a wave length modulation system, an electron discharge device having oscillation generating electrodes including an anode-like electrode, a control electrode and a cathode in an oscillation generating circuit including reactance and an additional electron receiving electrode coupled to the generating electrodes by the electron stream of the device, a connection for applying positive potential to said anode-like electrode, a load impedance for applying direct current potential of less value to said additional electrode, a phase shifting reactance coupling said electron receiving electrode to said control electrode for feeding thereto a voltage of the generated frequency displaced in phase with respect to the generated voltage on said control electrode, whereby a reactive effect is produced which supplements the reactance of said generating circuit and influences the frequency of operation of said oscillation generating circuit, a source of signal potentials, and means coupling said source of signal potentials to said additional electrode in said device to control the voltage thereof and thereby correspondingly control said reactive effect and the frequency of the oscillations generated.

8. In a wave length modulation system, a pair of electron discharge systems each having oscillation generating electrodes including a control electrode coupled in an oscillation generating circuit and each having an additional electron receiving electrode coupled to the generating electrodes by the electron streams of the system, a load impedance connecting to each of said additional electrodes, separate phase shifting reactances coupling the electron receiving electrode of each system to the control electrode of each system for feeding to said control electrode voltages of the generated frequency displaced in phase with respect to the generated voltage on said control electrodes whereby reactive effects are produced across said reactances and supplied to said generating circuit to influence the frequency of operation of said oscillation generating circuit, a source of control potentials, and means coupling said source of control potentials to the electron receiving electrodes in said systems to control the voltage thereof and thereby correspondingly control said reactive effects and the frequency of the oscillations generated.

HOWARD C. LAWRENCE.
